UNITED STATES PATENT OFFICE

MARIUS LATOUR, OF PARIS, FRANCE, ASSIGNOR TO LATOUR CORPORATION, OF JERSEY CITY, NEW JERSEY, A CORPORATION OF DELAWARE

RADIO SIGNALING SYSTEM

Application filed August 19, 1921, Serial No. 493,665, and in France September 27, 1915.

(GRANTED UNDER THE PROVISIONS OF THE ACT OF MARCH 3, 1921; 41 STAT. L., 1313)

Application filed in France, September 27, 1915, patented February 23, 1920, under 502,476.

In electrical vacuum tube relays (or tubes filled with ionized atmosphere) that have been suggested by various inventors, it may be advantageous under certain conditions (radiotelegraphic or radiotelephonic receiving on airplanes, receiving station located near an industrial network) to substitute an alternating potential source in place of the battery inserted in the plate-filament circuit of the said relay. By means of 55 transformers, this alternating potential may be stepped up to the desired value.

A local alternating current source being available, the desired object may be attained by transforming the character of the current through the agency of two kenotrons of the General Electric Company type and to return to the condition of direct current potential. But in this case, the resistance of the kenotrons is introduced into the circuit and it may be found advantageous directly to utilize the alternating potential without changing its character. This may be accomplished in the following manner, reference being had to the accompanying drawing in which

Fig. 1 diagrammatically represents a network including a vacuum tube in which the usual direct current plate supply source is replaced by a source of alternating current.

Figs. 2 and 2a are modifications of Fig. 1 showing the use of two vacuum tubes connected in push-pull relation in a similar network.

Fig. 3 is a modification of Fig. 1 for a system employing a double-element tube, in which the input and output electrodes are connected in push-pull relation.

Fig. 4 is a modification of Fig. 3 for a system in which the input and output electrodes are connected in parallel and push-pull relation respectively.

In accordance with the invention, as illustrated, in Fig. 1 of the drawings, the usual battery of the plate-filament circuit P, F is replaced by a network of any periodicity f_1 , which, however, is different from the periodicity f_2 of the current to be amplified. While the potential of f_2 frequency is not applied to the grid filament circuit GF, the tone corresponding to frequency f_1 will be heard in the telephone T. As soon as the potential of f_2 frequency actuates the grid filament circuit, in addition to the tone of f_1 periods, the tone of f_2 periods will be heard but the latter will be slightly confused.

In accordance with the present invention, a circuit arrangement is provided for eliminating from the telephone circuit the tone corresponding to the frequency f_1 of the network and for bringing out the tone corresponding to the current to be amplified, the frequency of which is f_2 . Fig. 2 represents such circuit arrangement comprising two tubes L and L'. The secondary windings of the induction coils B, B' are connected in opposition and the source of f_2 frequency operates through a transformer, the middle point of the secondary winding E of which is connected with the filaments F and F'. It will be seen, therefore, that the effects of the current of f_1 frequency will be subtracted from each other in the telephone T, while the tones of f_2 periods emanating from the two tubes will be added to each other in this telephone. If the two tubes are exactly alike, the tone corresponding to frequency f_1 may be completely eliminated. The best conditions for this circuit arrangement are obtained with a single tube provided with two plates and two grids, e. g. the special tube manufactured by the General Electric Company. A circuit arrangement in which a single tube of this type is used is shown in Fig. 3. The operation of

this circuit will be clear from what has been said in connection with Fig. 2.

If continuous radio telegraphic waves are used, a detector D, as illustrated in Figure 5 2a, should be provided in each of the telephone circuits at points "x" on Figures 2, 3 and 4. The proposed circuit arrangement is a circuit for direct receiving, the alternating current source performing the function 10 of a ticker.

With four tubes or two tubes of the special type, the character of the tone of f_2 periods which exists with the circuits of Figs. 1 and 2 may be further improved.

15 Fig. 4 shows an improved circuit arrangement in which a single tube is used. The tone corresponding to frequency f_1 is eliminated by means of an auxiliary winding α provided on the single transformer B. The 20 effect of this winding α is regulated by means of a resistance R. A represents an auto-transformer divided into two equal parts between which one of the three windings of the transformer is connected. The 25 middle point of this winding is connected to the common filament F, and the winding may be divided into two sections connected in series with the plates P and P', respectively, etc.

30 This circuit arrangement uses two half waves of the f_1 frequency network, which replaces the usual direct current source and makes thus possible the use of the relay for 35 wireless or wire telephone. In the case of wireless telephony, the same machine could be alternately used either as a generator, by utilizing the well known Meissner circuit arrangement for producing high frequency currents, or with the present circuit as a 40 source of f_1 frequency. The arrangement has particular advantages in case a very light station is desired for airplanes, the same station comprising sending as well as receiving means.

45 Having described my invention, what I claim is:

1. A wireless telegraph receiving system 50 adapted for reception of interrupted incoming high frequency waves wherein the interruptions correspond to the spaces between the dots and dashes of telegraph signals, said system comprising a circuit including a source of fluctuating current of audible frequency, an indicating device, said circuit being normally so balanced with respect to 55 said indicating device and said source of current that said indicating device is substantially unaffected by said fluctuating current, and means responsive to the incoming 60 signal impulses for upsetting the aforesaid balanced condition coincidentally with the duration of the incoming signal impulses whereby said fluctuating current is rendered effective to actuate said indicating device 65 and thereby reproduce the signal impulses.

2. A wireless telegraph receiving system 70 adapted for reception of interrupted incoming high frequency waves wherein the interruptions correspond to the spacing of the signal impulses, said system comprising a circuit including a source of fluctuating current, a translating device, said circuit being normally so balanced with respect to said device and said source of current that said translating device is substantially unaffected 75 by said fluctuating current, and means responsive to the incoming signal impulses for upsetting the aforesaid balanced condition coincidentally with the duration of the incoming signal impulses whereby said fluctuating current is rendered effective to actuate said translating device and thereby to enable the reproduction of the signal impulses.

3. A high frequency wave signal receiving 80 system adapted to receive wireless telegraph signals, said system comprising a plurality of three-electrode vacuum tubes each having an input circuit and an output circuit, a source of alternating current of audible frequency for energizing said output circuits, a signal indicating device operatively associated with at least one of said output circuits, balancing means normally operable 85 to prevent said fluctuating current from actuating said signal indicating device, and means responsive to incoming signal waves to upset the normal balanced condition whereby said indicating device is actuated by said fluctuating current in conformity 90 with incoming signal wave impulses.

4. In a wireless telegraph receiving system, a source of incoming signal waves, two complementary circuits, each including a space discharge path and an impedance in 105 series therewith, a source of fluctuating space current of audible frequency, said source being connected to both of said complementary circuits and adapted to supply the space current for said discharge paths, an additional circuit coupled with said complementary circuits conjointly, said complementary circuits being normally balanced oppositely in their effect upon said additional circuit so that normally there is substantially 110 no fluctuating current of audible frequency in said additional circuit, a signal indicating device responsive to audibly fluctuating current in said additional circuit, and an input circuit operatively associated with said complementary circuits conjointly and operable 115 to upset the aforementioned balanced condition upon being energized by incoming signal waves, said input circuit being coupled to said source of incoming signal waves, the arrangement being such that said additional circuit is energized by said source of fluctuating space current coincidentally with the duration of the unbalanced condition.

5. In a wireless telegraph receiving sys- 120

tem, a source of incoming signal waves, a pair of three-electrode vacuum tubes each having an input circuit and an output circuit, said input circuits being coupled conjointly to said source of incoming signal waves, said output circuits each including the space discharge path of one of said tubes respectively, a source of alternating current connected to supply space current to both of said output circuits, and a signal indicating device operatively coupled to said output circuits conjointly, said output circuits being electrically balanced in their normal relation to said indicating device so that in the absence of incoming signal waves the fluctuating space current in said output circuits does not materially affect said indicating device, said incoming circuits each including a control element, which elements are interposed respectively in the two discharge paths of said output circuits and operable to oppositely vary the impedance of said discharge paths in response to energization of said input circuits by incoming signal waves thereby upsetting the equipoise of said output circuits and permitting said alternating space current to actuate said indicating device to reproduce the signals.

6. The method of signaling by means of electric waves interrupted in accordance with telegraph signals which comprises, identically impressing across a pair of ionized space paths a fluctuating voltage, causing the resulting space currents to flow in opposition whereby normally the resultant effect is substantially zero, oppositely controlling said space currents with said electric waves, whereby additive space currents are produced, and causing said additive currents to be suitably indicated.

7. The method of signaling by means of electric waves interrupted in accordance with telegraph signals which comprises identically impressing upon a pair of ionized space paths an alternating voltage, causing the resulting space currents to flow in opposition whereby normally the resultant effect is substantially zero, oppositely controlling said space currents with said electric waves whereby additive space currents are produced, and producing indications by means of said additive currents.

8. In a radio telegraph system, the method of signaling which comprises, identically impressing upon a pair of ionized space paths, a voltage alternating at audio frequency, causing the space currents to flow in opposition whereby normally the resultant effect is substantially zero, oppositely controlling said space currents with unmodulated electric waves of radio frequency interrupted in accordance with telegraph signals for producing additive space current components and causing said additive currents to be indicated.

9. In a radio telegraph system, the method of signaling which comprises identically impressing upon a pair of ionized space paths an alternating voltage, causing the resulting space currents to flow in opposition whereby normally the resultant effect is substantially zero, oppositely controlling said space currents with radio telegraph signals to produce additive space currents, detecting and indicating the resulting currents.

10. In a radio telegraph system, the method of signaling which comprises, identically impressing upon a pair of ionized space paths a voltage alternating at audio frequency, causing the space currents to flow in opposition for normally producing substantially zero resultant effect, oppositely controlling said space currents with continuous wave radio-frequency telegraph signals to produce additive modulated currents, detecting and receiving the resulting currents.

11. In a radio-frequency telegraph system, the method of signaling which comprises identically impressing upon a pair of ionized space paths, unmodulated radio frequency waves interrupted in accordance with telegraph signals, oppositely controlling said space currents at an audio frequency to produce additive modulated space currents, detecting and receiving the resultant currents.

12. In a radio telegraph system the method of signaling which comprises, identically impressing upon a pair of ionized space paths a voltage alternating at a certain frequency, causing the space currents to flow in opposition whereby normally substantially no resultant effect is produced, oppositely controlling said space currents with electric waves of a second frequency interrupted in accordance with telegraph signals to produce additive modulated space currents, detecting and indicating the resultant currents.

13. In a radio telegraph system the method of signaling which comprises, identically impressing upon a pair of ionized space paths a fluctuating voltage, causing the space currents to flow in opposition whereby normally substantially no resultant effect is produced, oppositely modulating said space currents in accordance with radio telegraph signals for producing additive effects, detecting and receiving said modulated currents.

14. The method of radio signaling which comprises, identically impressing upon a pair of ionized space paths an alternating voltage, causing the space currents to flow in opposition to normally annul one another, oppositely modulating said space currents with unmodulated radio-frequency signaling waves interrupted in accordance

with telegraph signals to produce additive resultant space currents, detecting and receiving the modulated space currents.

15. In a radio system the method of signaling which comprises identically impressing upon a pair of ionized space paths a voltage alternating at audio-frequency, causing the space currents to flow in opposition to normally annul one another, oppositely modulating said space currents in accordance with interrupted single frequency radio telegraph signaling currents to produce additive modulated space currents, detecting and receiving the resultant currents.
